UNITED STATES PATENT OFFICE.

FRANCIS I. DU PONT, OF WILMINGTON, DELAWARE, ASSIGNOR TO DELAWARE CHEMICAL ENGINEERING COMPANY, OF WILMINGTON, DELAWARE, A CORPORATION OF DELAWARE.

STEAM GENERATOR.

Application filed August 24, 1922. Serial No. 583,956.

This invention relates to an improvement in steam generators and more particularly to generators for automobiles.

A steam generator for automobiles is subjected to different requirements than are other steam generators in that sudden and copious drafts are made upon it, and which drafts are generally of short duration.

The steam generator together with its furnace of a known type of steam driven automobile is not probably over three or four horse-power, while the engine is capable of delivering about seventy-five horse-power, with steam delivered thereto at the pressure generally carried in generators for steam driven automobiles.

It will readily be appreciated that as such generators are required to deliver for a short time steam at a rate greatly in excess of the rate at which the steam is generated by transmission of the furnace heat to the water in the boiler, the boiler must afford a reservoir of energy to be drawn upon whenever power greater than the average is needed.

The reservoir of energy is afforded by a mass of water heated to about 490° F. and consequently exerting a steam pressure of 600 lbs. per square inch.

When the engine throttle is opened, a very considerable amount of energy is available for use at as rapid a rate as may be needed. A well made steam automobile will on this account spurt up any ordinary hill at almost any desired speed without the necessity of changing gears. The pressure in the boiler will fall from say 600 lbs. to the sq. inch to 500 lbs. or perhaps to 450 lbs., but practical experience shows that there is always time for the normal pressure of 600 lbs. to recover before the next hill is reached.

When steam is generated from water under the conditions just described, every cubic inch of the water is instantly filled with bubbles, so that the whole mass of water rises, and unless the construction of the boiler is such as to take this into account, a very considerable amount of water passes over bodily into the cylinders of the engine. This causes a tremendous loss of efficiency as well as interfering with the proper mechanical performance of the engine.

The object of my invention is to provide a generator for a steam driven automobile which will deliver dry steam to the engine

regardless of the rate of generation or foaming caused thereby.

Another object of my invention is to provide a generator of this type which will be stayed in such a manner that it will not tear open over a large area if for any reason a rupture should take place, but confine such rupture to a small area and thereby avoid an explosion.

My invention provides a steam generator which will have the safety features of a water tube boiler, and the "reservoir power" features of a fire tube boiler.

In fact, the reserve power feature ought to be greater than the usual fire tube boiler as not only is the horizontal area at the water level greater, but there is a means of deterring the foaming which necessarily takes place in any boiler when sudden drafts are made upon it.

Another object of my invention is to provide a boiler which can have any shape as to horizontal cross-section without lessening its ability to withstand internal pressure.

The precise nature of my invention will be best understood by reference to the drawings, which will now be described and in which I have shown two specific forms of my invention, it being premised, however that changes may be made in the form and construction without departing from the spirit and scope of my invention as defined in the appended claims.

Fig. 1 is a vertical section of one form of generator built in accordance with my invention.

Fig. 2 is a detail sectional view showing the connections between the crown-sheet and the water tubes and between the crown-sheet and one of the stay bolts.

Figs. 3, 4 and 5 are sectional views through a portion of the generator on the lines 3, 4 and 5 of Fig. 1.

Fig. 6 is a detail sectional view showing one form of staying opposite sheets to each other by means of bolts.

Fig. 7 is an enlarged sectional view through the joints between side-forming members and the stay sheets.

Fig. 8 is a vertical sectional view through a modified form of boiler.

The generator shown in Figs. 1-5 comprises a steam delivery chamber *a* formed of a crown-sheet or bottom plate *b*, a top plate *c*, side members *d* and stay sheets *e*,

secured to each other as hereinafter described. Secured to the crown-sheet *b* and opening into the chamber *a* are the upper ends of a plurality of rows of vertical tubes. 5 Each row comprises a tube *f* and a plurality of shorter tubes *g*. The lower ends of all of tubes *f* are connected to a transverse header *h*, while the lower ends of all of the tubes *g* of each row are connected to a longitudinal header *i*. One end of each header *i* is closed, while the other end thereof is connected to the tube *f* in the same row. The various tubes are preferably welded to the crown-sheet *b* and to each other at the junction. 15

The side members are of U-form and the ends of the legs are preferably brazed to the top plate *c*, crown-sheet *b* and stay plates *e*.

20 The members *d* may be reinforced by means of semi-circular pieces *q* brazed to the inner surfaces thereof, as shown in Fig. 3.

Extending through the chamber *a* and secured to the top plate *c* and crown-sheet *b* 25 are a plurality of stay bolts *j* which are staggered with relation to the tubes *g* and *f*. These stay bolts may be of any well known form and may be secured to the top plate by nuts *k* and a special safety arrangement 30 to be hereafter described. In the form shown, the bolts are threaded at both ends and are provided with a reduced body portion between the threaded ends.

The crown-sheet may be reinforced at the 35 threaded bolt openings as shown at *l* in Fig. 2.

The stay sheets *e* are provided with relatively large openings *m* for all of the bolts *j* with the exception of the outer transverse 40 and longitudinal rows, as indicated at *n*. These holes *n*, Fig. 3, are preferably of a size to freely permit entrance of the threaded ends of the bolts and the tap for threading the openings in the crown-sheet.

45 Surrounding some of the front tubes *g* of all of the rows are square plates *p*, which together form a baffle plate for directing the flow of gases back and then forth among the tubes as indicated by the arrows in Fig. 1.

50 I have not shown the combustion chamber in connection with the generator, as this may be of any approved type.

The water line is maintained above the 55 crown-sheet as indicated in Fig. 1. Water is delivered to header *h* from which it passes to the lower ends of tubes *f* and from there to tubes *g* through headers *i*. Steam is drawn from the upper part of chamber *a* above the upper stay sheet *e*. These stay 60 sheets are preferably formed of heavier gage sheets than the top plate or side members in view of the reduction in tensile strength caused by the openings through which the bolts pass. These sheets *e* not only act as lateral stays for the sides of the chamber,

but also form baffles or separators for separating the water from the steam so that relatively dry steam is delivered from the steam space of said chamber from between the top plate *c* and the upper stay plate *e*.

70 The exact functioning of these plates in their prevention of foaming over may be described as follows: When the mass of water begins to rise in the boiler on account of violent boiling in one place or on account of 75 generation of steam from the whole mass of water as when an engine throttle is suddenly opened wide, the mass of bubbles encounters the first baffle plate above the water lever and has to pass in a series of even jets into the 80 space between it and the next plate above. Before passing to the similar space above, it has an opportunity to even up and separate the water remaining in the lower part and steam in the upper part, before proceeding 85 further upward.

The spaces between the baffle plates (or stay plates) therefore act as a series of separating chambers and even if the separation is not complete in the first space above the 90 water level, there will be more steam and less water in what rises to the next space above. This condition will always exist so that with a sufficient number of chambers (which need not be many) a complete separation of water 95 and steam takes place.

In Fig. 6 is shown a safety arrangement adapted to release the pressure in the boiler upon the failure of any one of the stay bolts.

Were something of this kind not provided, the failure of one stay bolt would throw 100 great additional pressure on those immediately around it, and if one of these should fail the pressure would still further increase on the surrounding bolts.

105 Finally when there was sufficient unstayed area this would burst out and since the area opened up would be large the bursting would amount to an explosion. This is true of any boiler or vessel as ordinarily constructed to 110 resist internal pressure by means of stay bolts.

In Fig. 6, *j* is the stay bolt. *c* is the top plate with its holes larger than the stay bolts, *3* is a relatively thin sheet of copper 115 extending over the plate *c* brazed to the top plates *c* along its edges as at 10 and having holes just large enough for the stay bolts. *4* is a cap having an external and internal thread. In assembling the boiler, this cap is 120 screwed down snugly and brazed only to the copper plate *3* at points 5, but not to anything else.

125 This having been done, a square washer 7 is put on and held firmly down on the sheet copper *3* by the nut *k*, which screws on the external thread of the cap *4*.

With the structure described it will be observed that the pressure in the boiler will 130 not blow out the copper sheet *3* so long as

the stay bolt holds, since the copper sheet spanning the area of the stay bolt hole not occupied by the stay bolt is backed by the cap 4 threaded on the bolt and which serves to hold the washer 7 against the plate 3 adjacent the edge of the hole through the engagement therewith of nut *k*. However, should a stay bolt break, the cap will be freed from the plate 3 as will the washer 7 and the pressure in the boiler will blow out the unsupported plate. The object of this construction is to insure that upon the failure of one stay bolt the pressure will be released instead of increasing the load on the surrounding bolts.

Another safety feature in this improved boiler is in the side construction and stay plates. This is shown in detail in Fig. 7. Here *e* are the stay plates and *d* are the U-shaped channels, which may be made by slitting a steel tube in half longitudinally. These are preferably brazed at points 9 to the plates and in the manner shown. The reason I prefer brazing to welding here is that the stay plates themselves are not melted or in any way changed by the operation. Now if the internal pressure should become too great, one of the U-channels or half tubes *d* would burst out in one place just as one of the tubes in a water tube boiler bursts under similar stress. There is, however, no conceivable way in which a burst or tear in the U-channels *d* could extend across the stay plate to the next U-channel beyond. In this way, the boiler is much safer than any construction in which a larger external shell withstands the pressure, for in this case when the internal pressure is too great for the shell a tear undoubtedly starts in one place, but the shell being uniform it proceeds instantly along or around the shell and opens up a large area out of which the contents of the boiler escape with explosive violence.

In Fig. 8 I have shown a boiler without water tubes and in which the opposite end plates or top and bottom plates *c*' and *b*' are connected to each other by means of fire tubes *j*' which also act as stay bolts or rods.

In this form, there are no water tubes, the water being heated by the hot gases which pass through the tubes *j*'. These tubes *j*' are welded to sheets *b*' and *c*' and pass through openings *m*' in stay sheets *e*'. These stay sheets *e*' are connected at their edges to side-forming members *d*' as in the structure above described.

The advantages of my invention result from the provision of a steam generator in which the side wall stays connect all the side walls to each other throughout the length of the side walls and which stays are spaced from each other to form a chamber having a plurality of interconnected compartments, whereby the steam is separated from the water. Also from the provision of such side

wall stays which will permit forming sectional side walls the different members of which are separated by the stays, the various stays being so arranged that the wall-forming portions of the chamber do not form a continuous sheet through which a rupture if started could be propagated. Also from the provision of a generator in which the end walls are stayed by means of stays which extend through openings in the side wall stays. Further, from the provision of a steam generator having a plurality of tubes communicating at one end with a common chamber having stays connecting the upper and lower walls to each other, as well as stays connecting opposite side walls to each other. Further, from the provision of a generator which can be made of any desired shape without interfering with the strength factor.

Having now fully described my invention, what I claim and desire to protect by Letters Patent is:

1. A steam generator having end sheets, a plurality of side-forming members for forming each side, transverse stay members, the side-forming members of each side being secured to the transverse stay members independently of each other, and stay members connected to the end sheets, there being openings through the transverse stays through which the end sheet stay members extend.

2. A steam generator having end sheets, a plurality of side-forming members for forming each side, stay sheets substantially parallel with the end sheets, the side-forming members on each side being connected to said stay sheets independently, said stay sheets acting as stays for the side-forming members around the entire generator and forming partitions in the generator, and stay rods connected to the end sheets and extending through openings in the stay sheets.

3. A steam generator having end sheets, four sides each of which is formed of a plurality of adjacent channel members, stay sheets extending from side to side both laterally and transversely between the legs of the channel members and connected thereto independently, and stay rods connected to the end sheets and extending through openings in the stay sheets.

4. A steam generator comprising a plurality of substantially vertical water tubes connected to each other for circulation at their lower ends and connected directly at their upper ends to a steam and water drum, the drum having side and end walls, stays connecting the end walls to each other at a plurality of points over their entire area, and a plurality of perforated stay sheets connecting the side walls to each other at a plurality of points over their length and height.

5. A steam generator comprising a plurality of water tubes connected to each other for circulation at one end and connected directly at the other end to a steam and water drum, the drum having upper and lower walls, spaced stay bolts connecting the upper and lower walls to each other, and spaced stay plates connected to all of the side walls, said stay plates having openings 10 through which the stay bolts extend.

6. A steam generator comprising a plurality of substantially vertical water tubes connected to each other for circulation at their lower ends and connected directly at 15 their upper ends to a steam and water drum of rectangular form, the drum having upper and lower walls, spaced stay bolts connecting the upper and lower walls to each other, and spaced stay plates connected to all of the 20 side walls, said stay plates having openings through which the stay bolts extend.

7. A steam and water drum for a steam generator having top and bottom plates, the bottom plate being arranged to be connected 25 to the upper ends of water tubes, regularly spaced stay bolts connecting the top and bottom plates to each other, the side walls being each formed of a plurality of members, and tie plates parallel with the top and bottom plates, said tie plates being secured between adjacent side wall-forming members, said tie plates having openings therethrough through which the tie rods extend.

8. A steam generator having substantially 30 vertical water tubes connected to each other at their lower ends by headers, a steam and water drum connected to the upper ends of said tubes, said steam and water drum being formed of a plurality of channel-shaped 35 side members in different horizontal planes, a bottom plate connected to the lower flanges of the lowermost side-forming members, said bottom plate being connected to the upper ends of the tubes, a top plate connected to 40 the upper flanges of the uppermost side-forming member, a tie plate interposed between adjacent side-forming members and connected to the upper flange of one member and the lower flange of the upper member, 45 and stay bolts connected to the upper and lower plates, the tie plates having openings through which the stay bolts extend, some of said openings being large relative to the bolts, to permit circulation of water and the 50 passage of steam to the upper portion of the drum.

9. In a steam and water drum for a steam generator, a top and bottom sheet, a perforation in the top sheet for the passage 55 of a stay bolt, a perforated plate superimposed on said top sheet, means for preventing steam from leaking out between the plate and the top sheet, a stay bolt passing through both perforations, means preventing

steam from leaking out between the stay 65 bolt opening in the plate and the bolt, and other means associated with the bolt for holding the plate in position on the top sheet.

10. A steam and water drum for a steam 70 generator having top and bottom plates the top plate being perforated for the passage of a stay bolt, a plate of relatively light material perforated for the reception of an end of a stay bolt, superimposed on said top 75 plate, means for securing said stay bolt to said superimposed plate and means for securing said superimposed plate to said top plate through the medium of said stay bolt.

11. A steam and water drum for a steam 80 generator having top and bottom plates, the top plate being perforated for the passage of a stay bolt, a perforated plate superimposed on said top plate, a stay bolt, a cap 85 engaging the end of the stay bolt and secured to said superimposed plate and means engaging the said cap adapted to secure said superimposed plate to said top plate, through the medium of said stay bolt.

12. A steam generator having an end sheet 90 stayed to another portion of the generator by a stay bolt, said sheet having an opening therethrough through which the stay bolt passes, a superimposed plate on the end sheet surrounding the bolt and secured to 95 the end sheet at a distance from the stay bolt to prevent leaking, and stay bolt securing means secured to the bolt and adapted to hold the plate in contact with the sheet.

13. A steam generator having an end 100 sheet stayed by means of a plurality of stay bolts extending from another portion of the generator through openings through the sheet said openings being of substantially 105 greater diameters than the diameters of the bolt, a relatively thin plate superimposed on the end sheet and secured at its edges to the end sheet, said sheet having openings through which the bolts extend, a threaded head on each bolt secured to the superimposed sheet, a washer surrounding each bolt head and engaging the superimposed sheet, and a nut on each head for drawing the washers into holding position on the plate. 110

14. A steam and water drum for a steam 115 generator comprising top and bottom and side plates, a plurality of rigid continuous sheets extending transversely of the drum and connected to all sides thereof, and stay bolts extending between the top and bottom 120 plates, said sheets being provided with perforations of greater diameter than that of the stay bolts through which the stay bolts pass in their extension.

In testimony of which invention, I have 125 hereunto set my hand, at Philada., Penna., on this 9th day of August, 1922.

FRANCIS I. DU PONT.
